COMBINED SHAVING BRUSH AND RAZOR
UNIT

Frank Broes, Sr., Palm Springs, Calif.

Application January 6, 1951, Serial No. 13,699

Term of patent 14 years

(Cl. D22—3)

To all whom it may concern:

Be it known that I, Frank Broes, Sr., a citizen of the United States, residing at Palm Springs, State of California, have invented a new, original, and ornamental Design for a combined Shaving Brush and Razor Unit, of which the following is a specification, reference being had to the accompanying drawing, forming a part hereof.

Figure 1 is a perspective view of a combined shaving brush and razor unit, showing my new design in the closed position;

Figure 2 is a perspective view thereof with the brush end cover removed;

Figure 3 is a perspective view thereof with the razor end cover removed;

Figure 4 is a side elevational view thereof with the covers in place; and,

Figure 5 is a bottom plan view thereof with the covers in place.

I claim:

The ornamental design for a combined shaving brush and razor unit, as shown and described.

FRANK BROES, SR.
